Application October 7, 1949, Serial No. 120,195

15 Claims. (Cl. 103—48)

1 This invention relates to lubricant dispensing pumps which are mounted directly upon a lubricant drum or container, the pump having an elongated cylinder submerged in the lubricant to deliver it under pressure from the drum to the point of use. Such pumps are applied to pressure lubrication generally, and are used most extensively in service stations for chassis lubrication jobs, the pump unit serving to withdraw the lubricant from its shipping drum for discharge under pressure into one or more flexible delivery tubes. These tubes are equipped with control nozzles which can be coupled conveniently to the grease fittings of automobiles, trucks or the like for pressure injection of the lubricant directly into the fittings.

It is essential for efficient operation of a dispensing pump of this nature that the delivery chamber of the pump cylinder be filled completely with a fresh charge of lubricant upon each stroke of the pump piston, otherwise the pump operates at reduced capacity. In pumping ordinary liquids, such as oils or light greases, this is not a serious problem since such lubricants flow readily into the pump cylinder while back flow can be controlled by a simple arrangement of check valves. However, in dispensing heavy oils and greases having limited flowability, it is difficult to charge the cylinder because of lubricant sluggishness; furthermore, the pump cylinder is apt to become air bound after a period of service, rendering the pump partially or wholly inoperative until it is serviced.

The principal objects of the present invention have been to overcome these problems by the provision of an improved pump structure combined with a piston-type air motor which is arranged to force a full charge of lubricant into the cylinder upon each stroke in spite of lubricant flow resistance, and to provide a combination of check valves and pistons which eliminate air which may be entrained in the grease by delivering the air through the pump to the delivery nozzle in an automatic manner, thus preventing the pump unit from becoming air bound. The structure thus provided performs its function in a more efficient and reliable manner than those used in the past and is of exceptionally simple and inexpensive construction.

Briefly, the improved pump unit consists of an air motor of the piston type, operating in conjunction with an elongated pump cylinder assembly which is arranged to be submerged in the lubricant contained in a drum so as to withdraw the lubricant from the drum by suction, force

5 it by positive displacement into the lower end of the cylinder, then to discharge the lubricant by positive displacement under high pressure from the upper end of the cylinder to the delivery line.

10 In order to provide a full intake charge for each pump stroke, the cylinder is provided with a pair of pistons and cooperating valves, one valve and piston for crowding a full charge of lubricant into the cylinder and the other for simultaneously delivering a charge under high pressure through the cylinder to the delivery line. Both pistons operate in tandem, being secured upon a single piston rod which is connected to the air motor piston for unitary reciprocation of the pistons. The lower or charging piston reciprocates in a charging chamber which develops a vacuum or partial vacuum in the charging chamber to admit lubricant into the chamber during the downward stroke of the piston; while at the same time, a charge is forced by positive displacement into the cylinder above the delivery piston. During the upward stroke, the fresh charge which was induced into the charging chamber is now forced under pressure into the cylinder, while at the same time, the preceding charge which is now above the delivery piston, is forced at high pressure by the delivery piston through the cylinder into the delivery line.

15 20 25 30 35 40 In order to assure a full lubricant charge for each delivery stroke of the high pressure delivery piston, the charging chamber is made larger in diameter than the cylinder bore of the delivery piston, whereby the lubricant charge which is forced from the charging chamber on the upward piston stroke, is greater than the delivery cylinder bore is capable of receiving; consequently, the charge is crowded into the cylinder under back pressure while the excess is by-passed under resistance. This insures complete filling of the cylinder above the delivery piston and forcibly displaces, along with the lubricant, any air which may be entrained or pocketed in the lubricant charge.

45 50 55 To promote further the efficiency and reliability of the apparatus, it is arranged to deliver lubricant under pressure during both piston strokes, thereby increasing output capacity and reducing pressure surges in the delivery lines. The pump thus constitutes a double acting pump in the sense that a major charge of lubricant is delivered under high pressure during the upward or delivery stroke of the piston rod while a secondary or minor charge of grease is delivered on the return or downward stroke at substantially

the same pressure. The minor discharge is brought about in a very simple manner by providing differential diameters on the piston rod, so that the piston rod itself produces a fractional displacement of lubricant from the cylinder during its downward movement.

The air motor piston includes major and minor air pressure areas which are correlated with the major and minor delivery areas of the pump assembly to develop a pumping force consistent with the resistance developed respectively during the upward and downward strokes of the piston rod. The minor piston area is under constant air pressure to force the piston rod downwardly after each upward stroke, serving coincidentally as above noted, to deliver the minor grease charge. The air motor is supplied constantly with compressed air and operates when the delivery line is open and stalls when the line is blocked; therefore, the lubricant is held under constant pressure in the delivery line or lines.

It is desirable to have the air motor stall with its major piston area subjected to air pressure so that lubricant is maintained in the lines under pressure by the delivery piston for immediate delivery when required and also to prevent leakage of air when the unit is not operating. This has been accomplished by correlating the air motor piston areas with respect to the grease displacement areas differentially so that the downward stroke presents less resistance than the upward stroke. This causes the pump piston to complete its downward stroke and stall at the beginning of its upward stroke after the discharge nozzle is blocked. The air motor is equipped with a reversing valve which is actuated by movements of the piston to provide sustained reciprocation. This valve is tripped to reverse piston movement at completion of the downward stroke and to seal itself against air leakage when it is positioned to drive the piston upwardly; consequently, air leakage is eliminated after the piston completes its down stroke and starts upwardly.

Further objects and advantages of the invention are more clearly disclosed in the specification in conjunction with the accompanying drawings.

In the drawings:

Figure 1 is a vertical sectional view illustrating generally the air motor and pump assembly.

Figure 2 is an enlarged fragmentary view of the lower portion of the pump cylinder illustrating the operation of the pistons and valves during the downward stroke of the piston rod.

Figure 3 is a fragmentary view similar to Figure 2, showing the operation of the parts during the upward or delivery stroke of the piston rod.

Figure 4 is an enlarged sectional view taken from Figure 1 further detailing the packing gland assembly at the outlet end of the pump cylinder.

Figure 5 is a sectional view taken on line 5-5, Figure 1, detailing the construction of the shuttle valve.

Figure 6 is a sectional view taken on line 6-6, Figure 1, detailing the construction of the lubricant charging inlet means.

Described with particular reference to Figure 1, the pump unit consists essentially of an air motor indicated generally at 10 having an air operated piston 11 and reversing valve 12, with an elongated pump cylinder 13 extending downwardly from the air motor. The lower end of the cylinder is provided with a lubricant charging

piston 15 secured upon a piston rod 16, which extends through the cylinder with its upper end connected to the air motor piston 11 for reciprocation. The air motor embodies a casing generally indicated at 17 which is machined to form a cylinder 18, and includes passageways which conduct compressed air from an intake passageway 20 the cylinder under control of the reversing valve 12. As shown, the air motor casing 17 is mounted upon a lid or cover plate 21 having a central opening 22 for the pump cylinder 13, the plate 21 preferably constituting a cover or lid which may be installed directly upon the original grease container.

Air motor

The pump is designed to lift and deliver the lubricant under high pressure during the upward or delivery stroke and also to deliver a small amount of grease during the downward or charging stroke, as more clearly disclosed hereinafter. For this purpose, the air motor piston is arranged to actuate the piston rod under maximum effective pressure during the upward or delivery stroke area to force the rod downwardly at less pressure by providing a reduced piston area on the upper side of the piston which is supplied constantly with air pressure. In other words, while the compressed air supplied to the cylinder through port 20 is in constant communication with the upper end of the cylinder to urge the piston downwardly, nevertheless, the effective piston area at the lower end of the piston is a multiple of the reduced area so as to force the piston upwardly to deliver lubricant at pressure sufficiently great for direct application to the bearing fittings.

In Figure 1, the lower or major piston area is designated at 23 and the minor area is designated at 24. As shown, the piston is approximately at its downward limit of travel, with the reversing valve about to be tripped to reverse the piston travel. The reversing valve 12 is actuated by a stem 25 which is slidably mounted in the motor casing 17 and connected to the piston 11 by an arm 26 slidably cooperating with the stem to elevate the stem toward the upper limit of piston travel and to lower the stem during the final downward movement of the piston, as indicated by the arrows. As shown, the lower portion of stem 25 embodies a necked portion 27 establishing a connection with a toggle lever 28 which is pivoted as at 29 and spring loaded by the compression spring unit 30 disposed above the pivot point. The toggle lever is arranged to snap the toggle past a dead center position to actuate the valve plunger 31 at the limits of piston travel. In the position shown in Figure 1, the valve plunger is in its open position to exhaust the air from the major piston area 23 by way of passageway 32 through the exhaust ports 33 of the valve. Compressed air is conducted to the minor piston area 24 by way of the supply port 20, vertical passageway 34 and lateral opening 35 through the wall of the cylinder. The spring loaded toggle lever 28 is shown near its dead center position so that the valve is about to be reversed by continued downward movement of the piston. When the toggle 28 snaps over, exhaust ports 33 will be blocked by the seat 36 of valve plunger 31 and the tapered seat 37 will be opened to admit air from vertical passageway 34, lateral passageway 38, through the valve to lateral passageway 32 which communicates with

the major piston area 23 to cause upward travel of the piston and delivery of grease.

When the pump is placed in operation, compressed air is supplied constantly to the air motor so that the lubricant supply lines are under pressure at all times with the air motor stalled against back pressure unless the line or lines are opened to permit the passage of lubricant and operation of the motor. At this point, it is to be noted that by reason of the constant compressed air supply to the minor piston area 24, coupled with the fact that the piston rod moves downwardly with minimum resistance, the air motor piston always completes its cycle of operation with the piston at its downward limit of travel. Thus, if the lubricant delivery line is blocked while the piston is moving in its downward stroke, it will follow through automatically until the piston trips the valve at its downward stroke limit. In this position, air is admitted to the major piston area, and the piston is stalled by lubricant back pressures and is ready to deliver lubricant immediately when the delivery line again is opened; also, seat 36 of the valve plunger 31 is closed to prevent leakage of air while the unit is stalled.

Pump cylinder assembly

The lubricant cylinder consists of three sections; an upper section 39 which may be designated as a delivery cylinder, an intermediate or displacement cylinder 40 and a lower or charging cylinder 41, the respective sections being screwed together as at 42-42. The cylinder is provided with a pair of pistons, the charging or primary piston 15 which reciprocates in cylinder 41 and a high pressure displacement or secondary piston 72 which reciprocates in the displacement cylinder 40; and the passage of lubricant is regulated by a shuttle valve 58 and a ball check valve 71. The upper end of the delivery cylinder 39 is screwthreaded as at 43 into a fitting 44 to which is connected a lateral delivery coupling 45 which preferably includes a check valve. Fitting 44 forms a part of a packing gland indicated generally at 46, and is clamped within a boss 47 formed as an integral part of the air motor casing 17. A clamping nut 48 is screwthreaded as at 49 into the boss, with its upper end engaged against a shoulder 50 formed in fitting 44. The lateral delivery tube 45 is screwthreaded into the fitting as at 51 and passes through an opening formed in boss 47. The delivery lines and dispensing nozzles do not form a part of the present invention, and since they are well known in the art, they are omitted from this disclosure. The delivery line, which consists usually of a flexible hose capable of withstanding high pressure, may be connected directly to the delivery coupling 45, or a plurality of flexible delivery tubes may be connected to a manifold pipe which is supplied from the coupling to provide multiple outlets from a single pump unit.

The upper end of the piston rod 16 is connected to the air motor piston 11 by a coupling 65 nut 52 threaded to the lower end of a thimble 53 formed as an integral part of the air motor piston. The coupling nut includes an internal shoulder 54 and the rod 16 includes a nut 55 screwthreaded upon its end and confined between the shoulder 54 and the thimble 53 to transmit the movements of the piston to the rod. A slight radial clearance is maintained around the nut and piston rod to permit the rod to align itself with respect to the piston 11 to prevent binding of the 70 piston.

parts. The lubricant charging piston 15 is clamped upon the lower end of the piston rod assembly between a shoulder 56 and a nut 57 screwthreaded upon a counter-turned portion of the rod.

The lower portion of charging cylinder 41 is provided with ports 61 which are traversed by piston 15 to charge the cylinder by suction on the downward piston stroke. The vacuum or partial 10 vacuum for inducing the flow of lubricant into the charging cylinder and for preventing back flow from displacement cylinder 40 is provided by a shuttle valve 58 which is slidably mounted upon the piston rod 16 and arranged to seat against the upper end of the charging cylinder during the downward stroke of the piston rod, as shown in Figure 2. The shuttle valve 58 consists essentially of a sleeve and its upper end is provided with spaced ears 59 engageable 20 against the shoulder 68 of cylinder 40 to limit upward movement of the valve and to provide lubricant passageways. The operation of the charging piston and shuttle valve is described with greater detail in a succeeding section of this specification.

Surrounding the ports 61 is a cylindrical perforate jacket or filter screen 62, consisting of an upper ring 63 slidably fitted upon cylinder 41 and a lower cap 64 screwthreaded as at 65 upon the lower end of the cylinder. A fine mesh cylindrical screen 66 is secured to the ring 63 and cap 64, spaced from the cylinder and enclosing the ports 61 to screen the lubricant which may pass into the lower end of cylinder 41. The cap 64 and ring 63 are secured together by a plurality of vertical rods 67, having their ends anchored in the cap and ring to space them and serving also to reinforce the screen 66 against collapse.

From the displacement cylinder 40 the lubricant passes through a ball check valve generally indicated at 71 and is discharged under high pressure by the displacement piston indicated generally at 72 reciprocating in the bore of cylinder 40. Described in detail, check valve 71 and piston 72 are interposed in the piston rod 16 by the provision of an insert tube 73 having its opposite ends screwthreaded as at 75 and 76 upon the adjoining ends of the piston rod sections. The piston 72 consists of a packing ring 77 (Figures 2 and 3) encircling the tube 73 and in sliding engagement with the bore of the displacement chamber. The packing ring may be formed from synthetic rubber or an appropriate plastic material having the necessary resiliency. The packing ring preferably is U-shaped in cross section and is expanded into sealing engagement by means of a pressure ring 80 which is T-shaped in cross section and interfitted with the ring. As shown, the tube 73 includes a head 81 against which the pressure ring is seated, and a leather ring 82 is placed against the packing ring 77. The two rings are clamped in compression against the head 81 by means of a spacer collar 83 engaged by a washer 84 which, in turn, is clamped against a shoulder 85 of tube 73 by the threaded upper end of the piston rod section. The spacer collar 83 preferably is formed of brass to provide a slide bearing with respect to the bore of the cylinder while the clamping washer 84 may be made of steel.

The insert tube serves also as a cage for the ball check valve 71 by the provision of a vertical bore 86 through tube 73 having at its upper end an enlarged bore 87 forming a tapered valve seat 88 cooperating with the valve ball 89. The lower end of passageway 86 communicates with the dis-

placement chamber by way of the lateral ports 90 formed in the lower piston rod section. The ball check normally is maintained in its closed position by the spring 91 which is maintained in compression between the ball and the end of the upper piston rod section. A spur 92 forming an extension of the piston rod, passes downwardly through spring 91 to maintain the spring in alignment with the ball. It will be observed in Figure 3, that the ball check 89 seats against back flow during the upward stroke of the piston rod for positive displacement of the lubricant under high pressure and unseats, as in Figure 2, during the downward stroke to permit lubricant trapped between the piston and shuttle valve to pass from the displacement cylinder to the delivery cylinder.

The packing gland assembly 46 at the top of the cylinder assembly provides a double packing, one of which is effective to seal the piston rod with respect to the air motor while the other prevents the escape of lubricant from the cylinder during delivery. The gland includes also a wiper ring interposed between the two packings which is arranged to wipe from the piston rod any lubricant which may adhere to it.

Described in detail with reference to Figure 4, the packing gland is enclosed by the boss 47 previously noted, and is clamped in position by the clamping nut 48 which forces the packing gland assembly upwardly against a shoulder 95 at the top of the boss. The air motor seal consists of a closure plate 96 having an internal groove 97 in which is confined a resilient sealing ring 98 formed of synthetic rubber or plastic embracing the piston rod to establish a seal between the air motor cylinder and rod. The plate 96 includes a shoulder 100, and a sealing gasket 101 formed of a material similar to packing ring 98 is maintained under compression between shoulders 95 and 100 to establish a seal.

The intermediate wiping ring 102 is seated against the lower side of closure plate 96 and is tapered in cross section to provide a feathered wiping edge. The wiping ring 102 is confined in a cage 103 which includes an internal bore provided with holes 104 communicating with a lateral passageway 105 to permit the lubricant to drain from the packing assembly through opening 22 back to the drum. The ring 102 is maintained in compression around the piston rod by a spring 106 mounted in compression within cage 103, having its upper end seated against a pressure ring 107. The pressure ring 107 includes a cone shaped recess in its upper face which engages the feathered lower end of the wiping ring to force the ring radially into a wiping engagement with the piston rod. Cage 103 is clamped against the closure plate 96 by the fitting 44 previously described.

The lower packing ring 108 which provides a lubricant seal around the piston rod, is mounted within the bore 110 formed in the upper end of fitting 44. Ring 108 also is feathered in cross section and is maintained in compression between the bore 110 and the piston rod by a shouldered ring 111 seated against the bottom of the bore, with its upper edge in compression against the packing ring. A washer 112 is placed above packing ring 108 in the bore 110 and the assembly is maintained in compression by the clamping nut 48.

Operation

In order to assure complete charging of the displacement cylinder 40 upon each stroke of the

charging piston 15, the bore of the charging cylinder 41 is somewhat greater in diameter than displacement cylinder 40. Otherwise expressed, the piston 15 tends to crowd a greater volume of lubricant into the displacement cylinder than it is capable of receiving, by reason of the differential in volumetric displacement between the two. Theoretically, this condition would impede operation of the charging piston 15 or jam it completely, since the lubricant is not compressible; however, a predetermined amount of clearance, indicated at 93, is provided between the diameter of the charging piston 15 and its bore whereby the excess grease is permitted to by-pass while under restricted flow and thus maintain loading pressure upon the lubricant above the piston. By this arrangement, complete charging of the displacement cylinder occurs on each stroke and the output of the pump is kept at maximum.

Lubricant is displaced upwardly through the cylinder assembly in several stages which can best be disclosed by identifying the successive chambers and the function of each. The chamber of charging cylinder 41 is indicated at A, the chamber of displacement cylinder 40 is indicated at B and the passageway of delivery cylinder 39 is indicated at C. During the downward or charging stroke of the piston rod, as shown in Figure 2, a vacuum or partial vacuum is developed in chamber A to load the chamber when the charging piston passes the ports 61 and, at the same time, lubricant which is trapped in chamber B between shuttle valve 58 and delivery piston 72, passes through the ball check valve 71 into the delivery chamber C, as indicated by the arrows. Primarily, therefore, the downward piston stroke loads chamber A with a fresh charge of lubricant from the drum, and simultaneously transfers the charge in chamber B to chamber C. A given charge of lubricant thus passes through three stages of displacement successively through the chambers A, B and C during one complete stroke cycle.

Upon execution of the upward or delivery stroke, as shown in Figure 3, the lubricant trapped in chamber A above charging piston 15 is forced into chamber B at a rate in excess of the displacement from chamber B to C by reason of the differential diameters of chambers A and B, as above noted. At the same time, the lubricant above the high pressure delivery piston 72 is forced under high pressure through the delivery chamber C to the outlet tube 45, the ball check valve 71 being, of course, closed to prevent back flow.

The cylinder assembly has been described up to this point as single acting in order to render more clearly its primary functions. However, in addition to recharging chamber A by vacuum and recharging chamber C from chamber B during the downward piston stroke, the assembly also discharges a limited quantity of lubricant at full pressure through outlet tube 45 during the down stroke. The cylinder assembly thus may be described as a modified double-acting unit. Otherwise expressed, the major high pressure discharge of lubricant occurs during the discharge or upward stroke (Figure 3) and a minor discharge at substantially the same pressure occurs during the charging or downward stroke (Figure 2) so that the discharge of lubricant occurs during both strokes of the cycle.

The minor or secondary discharge during the downward charging stroke occurs by reason of

a difference in diameter between the upper and lower sections of the piston rod assembly. As illustrated, the diameter of the upper rod section, which is indicated at D, is greater than the diameter E of the lower rod section to cause displacement of lubricant equal to the differential between rod sections D and E. Thus, during the downward stroke there is upward displacement of lubricant through the ball check valve 71 and, at the same time, rod section D is passing into chamber C through packing gland 46 and rod section E is passing out of chamber B through shuttle valve 58. Since the displacement of rod D which is entering the cylinder is greater than E, which is leaving the cylinder, a quantity of lubricant equal to the differential is discharged from the outlet tube 43.

In the present disclosure, the differential between sections D and E is sufficient to maintain full pressure at the delivery nozzle with a slight discharge of lubricant so as to eliminate substantially the surges in pressure which otherwise would occur during the pumping cycles. This has been found to improve efficiency since the volume displaced is increased and also because constant pressure is applied to the bearing being lubricated, thus giving the lubricant an opportunity to seep into the bearing during the return pump stroke.

As previously noted, the major area 23 of the air motor piston 11 is effective during the major delivery stroke of the high pressure delivery piston 12 and the minor area 24 is effective during the charging or return stroke. The major air piston area 23 is a multiple of lubricant piston area 72 and the minor air piston area 24 is a multiple of the displacement area provided by the differential rod sections D and E. Under a given set of factors as to input air pressure, grease viscosity and temperature, the pump is capable of delivering lubricant at approximately 6000 lbs. p. s. i. at maximum volume on the upward delivery stroke and to discharge lubricant at substantially the same pressure but at fractional volume during the return charging stroke.

The air motor is arranged to complete its downward stroke before stopping by reason of the constant piston return air pressure supplied to the minor piston area 24, as noted previously. Since air pressure is supplied constantly to air motor 10, and grease delivery is controlled at the nozzle by stalling the motor against grease back pressure, the charge of lubricant in the pump must be discharged into the blocked delivery line in order that the pump may complete its downward stroke. It is found that the flexible delivery hose will expand sufficiently to receive the balance of the discharge since the discharge volume is very slight in proportion to the hose area. This permits the piston to complete its downward discharge stroke and trip the valve toggle lever to deliver compressed air to the major piston area which will cause the piston 11 to begin its upward stroke, then stall against lubricant back pressure.

In order to cause the piston to complete its downward stroke in spite of the minor grease delivery resistance, the differential piston rod sections D and E are proportioned to require less piston rod force than the delivery piston 12, bearing in mind that the volume discharged is a small fraction of the major delivery volume. In other words, by correlating the major air piston area 23 to the delivery piston 12 to produce a given lubricant output pressure, and correlating the

minor piston area 24 with the differential rod displacement areas D and E to produce slightly greater output pressure, resistance on the down stroke is less than on the up stroke. This difference in resistance causes piston 11 to complete its down stroke before stalling, the effect being to unbalance piston pressure in the down direction. It has been found, by virtue of the arrangement of positive displacement chambers A, B and C, in combination with the shuttle and check valves, that the improved pump assembly discharges through the control nozzle any air which may be trapped in the grease. This eliminates the need of manually bleeding air, which in the past, frequently became trapped in grease pumps of this nature, rendering the pump inoperative. It is believed that air which may be drawn into the charging cylinder 41 with the lubricant, is displaced readily into chamber B by reason of low resistance and ample passageways through the shuttle valve 58. It is to be noted at this point that, by virtue of the slideable engagement of the shuttle valve with the piston rod, the valve is urged mechanically in its opening and closing movements by the piston rod itself instead of by the fluid pressure passing through it. In other words, since the valve is not spring loaded, flow resistance is reduced and the pump operates more efficiently. After passing into chamber B, the air is forced through ball check 71 by positive displacement since it is trapped between piston 72 and shuttle valve 58. It is found that if the pump is lifted out of the grease drum while running, then plunged back into the drum, the air that has been sucked into the pump is forced out ahead of the grease instead of causing the pump to become air bound.

It is found in practice, that the screen unit 62 surrounding the intake ports aids in charging lubricant into the charging chamber, causing the chamber to force a full charge into the displacement cylinder upon each upward stroke, and causing the cylinder in turn, to deliver lubricant at maximum volume upon each upward stroke of the high pressure delivery piston. The screen is of relatively fine mesh to filter out very fine solid particles and naturally resists, to a certain extent, the free passage of viscous lubricant. The piston moves more rapidly upon the downward or charging stroke than upon the upward or delivery stroke, consequently giving the lubricant a greater opportunity to flow inwardly through the screen than outwardly. Moreover, during the downward stroke of the charging piston, the piston has a displacement effect with respect to the lubricant within the strainer jacket which surrounds the lower portion of the cylinder. The impedance to the flow of lubricant through the meshes of the strainer, causes the strainer, in conjunction with the cylinder which it surrounds, to act as an annular trap with respect to the lubricant. The downwardly moving piston thus provides a laterally flowing stream of lubricant under the localized pressure of the piston and this stream is deflected by the jacket upwardly about the piston toward the open portion of the intake ports above the piston. Thus, the partial vacuum drawn by the piston is satisfied by directing streams of additional lubricant toward the ports by the sustained displacement effect of the piston during the remainder of the downward stroke. Maintaining flowing streams of lubricant internally of the strainer jacket toward the intake ports for the duration of the downward stroke is of particular advantage with

respect to stiff lubricants because it provides a time interval during which the slow moving lubricant may fill in any void which may exist in the charging chamber after the ports open. Tests have indicated that the output of the pump per stroke is measurably greater with the strainer installed on the charging chamber as shown, due to the baffle action of the strainer with respect to the lubricant, partially resisting the outward flow of lubricant under the displacement of the charging piston.

Ordinarily, the pump unit will operate satisfactorily without a check valve in the delivery coupling 45 since the piston stalls in the delivery stroke direction against back pressure. However, when several delivery lines are connected to a single pump, there is a tendency for the delivery piston to be forced downwardly by back pressure in the lines after stalling and for this reason the unit performs more satisfactorily with a check valve interposed in the line. As shown, the coupling 45 consists of a cage 115 loosely confining a ball 116 and provided with cooperating seat 117. The ball is maintained in the cage by a retainer 118 which is secured in position by a fitting 119 screwthreaded into the cage. When excessive back pressure prevails, the ball seats and prevents it from being imposed upon the pump piston.

Having described my invention, I claim:

1. A dispensing pump for viscous liquids comprising; a cylinder having a charging chamber at one end thereof and a delivery passageway at its opposite end, a primary and secondary piston slidable in said chamber and cylinder respectively, valve means operable to charge the cylinder and chamber upon movement of the pistons in the charging direction and to advance both charges upon movement of the pistons in the delivery direction whereby the charge in the charging chamber is forced under pressure into the cylinder and the charge in the cylinder is forced under greater pressure toward the said delivery passageway, and an air motor having a piston connected to the primary and secondary pistons for reciprocating the same, the air motor piston having a major area operable to thrust the pistons under high pressure during the delivery stroke of the pistons and a minor area for thrusting the pistons at low pressure during the charging stroke of the pistons, the minor piston area being under constant air pressure and the major area being supplied intermittently with air pressure to provide reciprocation.

2. A dispensing pump for viscous liquids comprising; a cylinder having respective charging and displacement chambers at one end thereof and a delivery passageway at its opposite end, respective pump pistons slidable in said chambers, valve means operable to charge both of said chambers with liquid upon movement of the pistons in one direction and to advance both charges under pressure upon movement of the pistons in the opposite direction, the said charging chamber having a greater displacement capacity than the displacement chamber to force the charge under pressure into the displacement chamber, and an air motor having a piston connected to the pump pistons for reciprocating the same, the air motor piston having a major area under intermittent air pressure operable to thrust the pump pistons at high pressure during the advancing stroke and having a minor area under constant air pressure operable to

thrust the pistons at low pressure during the charging stroke.

3. A lubricant dispensing pump comprising; an elongated cylinder having respective charging and displacement chambers at one end adapted to be submerged in the lubricant and a delivery passageway at its opposite end, respective pump pistons slidable in said charging and displacement chambers, valve means associated with the respective chambers operable to pass a charge of lubricant simultaneously from the charging chamber to the displacement chamber and from the displacement chamber toward the said delivery passageway during a delivery stroke of the said pistons and to block the back flow of lubricant during a charging stroke of the pistons, the said charging chamber having an intake port arranged to be traversed by the piston to induce a charge of lubricant into the chamber by vacuum upon the charging stroke of the piston, and an air motor having a piston connected to the pump pistons, the motor piston having a major area which is supplied intermittently with air pressure to thrust the pistons in their delivery stroke and having a minor area which is under constant air pressure to thrust the pistons in their charging stroke and develop the vacuum in the charging chamber.

4. A lubricant dispensing pump comprising; an elongated cylinder having respective charging and displacement chambers and a delivery passageway, respective pump pistons slidable in said respective charging and displacement chambers, valve means associated with the respective chambers operable to pass a charge of lubricant simultaneously through the charging and displacement chambers during a delivery stroke of the pistons and to block back flow of lubricant during a charging stroke of the pistons, the said charging chamber having an intake port which is traversed by the charging piston and arranged to induce a charge of lubricant into the chamber under vacuum developed in the chamber during the charging stroke, and a fluid pressure motor having a piston connected to the said pump pistons for actuating the same, the motor piston having a minor piston area which is under constant fluid pressure to drive the pump pistons in their charging stroke and having a major piston area under intermittent fluid pressure operable to drive the pump pistons in their displacement stroke against the constant force applied by the minor piston area.

5. A lubricant pump comprising; an elongated cylinder having respective charging and displacement chambers at one end thereof and a delivery passageway at its opposite end, respective charging and delivery pistons slidable in said charging and displacement chambers, a piston rod connected to said pistons and extending through the cylinder for reciprocating the pistons in unison in charging and delivering strokes, power means for reciprocating the piston rod, a valve seat interposed between the charging and displacement chambers, a movable check valve sleeve cooperating with said seat and slidably engaged upon the piston rod, the check valve sleeve being adapted to engage said seat and thereby block lubricant back flow during the charging stroke of the pistons and to develop a vacuum in the charging chamber during the charging stroke, the chamber having an intake port which is traversed by the charging piston to admit lubricant when the port is uncovered by the charging piston, a second check valve

operable to pass lubricant from the displacement chamber to the opposite side of the delivery piston during the charging stroke and to block lubricant back flow during the delivery stroke, the said piston rod having a major diameter slidably sealed with respect to the end of the cylinder and a minor diameter slidably sealed with respect to the movable check valve sleeve and adapted to displace a minor charge of lubricant from the cylinder during the charging stroke of the piston rod, whereby lubricant is discharged through the delivery passageway both during the charging and delivery strokes.

6. A lubricant pump comprising; an elongated cylinder having respective charging and displacement chambers at one end thereof and a delivery passageway at its opposite end, a respective charging and delivery piston slidable in said charging and displacement chambers, a piston rod connected to said pistons and extending through the cylinder for reciprocating the pistons in charging and delivery strokes, a seal for said rod at the end of the cylinder opposite to the charging and displacement chambers, a valve seat interposed between the charging and displacement chambers, a movable valve element cooperating with said seat and slidably engaged upon the piston rod, the movable valve element being adapted to block the flow of lubricant during the charging stroke of the pistons, the said piston rod having differential diameters passing through said seal and valve element adapted to provide a minor displacement of lubricant during the charging stroke of the rod and a major displacement during the delivery stroke, and an air motor having a piston connected to the said piston rod for actuating the same, the air motor piston having differential areas for reciprocating the piston rod at high pressure during the delivery stroke of the piston rod and at low pressure during the charging stroke of the piston rod.

7. A lubricant pump comprising; an elongated cylinder having respective charging and displacement chambers at one end thereof and a delivery passageway at its opposite end, respective charging and delivery pistons slidable in said charging and displacement chambers, a piston rod connected to said pistons and extending through the cylinder for reciprocating the pistons in unison, power means for reciprocating the piston rod in charging and delivery strokes, the said power means being adapted to reciprocate the piston rod at a rapid rate during the charging stroke and at a slow rate during the delivery stroke, a valve seat interposed between the charging and displacement chambers, a movable valve element cooperating with said seat and slidably engaged upon the piston rod to block lubricant back flow from the displacement chamber to the charging chamber during the charging stroke of the pistons and to develop a vacuum in the charging chamber during the charging stroke, the charging chamber having intake ports which are traversed by the charging piston, valve means operable to pass lubricant from the displacement chamber during the charging stroke, and a screen disposed in spaced relationship upon the charging chamber surrounding the intake ports to filter solid particles from the lubricant and to provide resistance to the flow of lubricant whereby lubricant pressure is developed within the screen by displacement of the charging piston at said rapid rate during the charging stroke to supplement the charging of lubricant through

the intake ports under vacuum when the ports are uncovered.

8. In a lubricant dispensing pump, a cylinder having a delivery passageway, a charging chamber at one end of the cylinder having an intake port, primary and secondary pump pistons disposed in the charging chamber and cylinder respectively, respective valves for developing negative pressure in the charging chamber for charging the same and for displacing lubricant through the cylinder during the strokes of the pistons, an air motor for reciprocating the pump pistons consisting of a cylinder having an air piston connected to the pump pistons, the air piston having a major area on one side and a minor area on its opposite side, means for admitting air pressure to the major piston area intermittently and for maintaining constant air pressure upon the minor area to cause reciprocation of the air and pump pistons whereby the minor area is effective for developing the said negative pressure in the charging chamber and the major area is effective for delivering the lubricant at high pressure from the pump cylinder.
9. In a lubricant pump, a cylinder having lubricant intake and delivery passageways, piston and valve means for displacing lubricant under pressure through the cylinder, a piston rod connected to the piston means having differential diameters passing through the opposite ends of the cylinder and arranged to provide a minor displacement of lubricant from the cylinder during the charging stroke of the piston, an air motor for reciprocating the pump piston consisting of a cylinder having an air piston connected to the said piston rod, the air piston having a major area on one side and a minor area on its opposite side, means for admitting air pressure to the major piston area intermittently and for maintaining air pressure constantly upon the minor area to cause reciprocation of the piston, the said major area being effective to drive the pump piston in its discharge stroke to deliver a major lubricant charge at a given pressure and the minor area being correlated to the differential piston rod displacement diameters to displace a minor lubricant charge during the charging stroke for delivery at greater pressure than the major discharge.
10. In a lubricant dispensing pump, a cylinder having lubricant intake and delivery passageways, piston and valve means for discharging lubricant under pressure through the cylinder, a piston rod connected to the piston means having differential diameters arranged to provide a minor displacement of lubricant from the cylinder during the charging stroke, an air motor for driving the pump, the air motor being supplied constantly with compressed air and arranged to deliver lubricant automatically and to stall at predetermined lubricant back pressure and having a piston connected to the said piston rod, the air motor piston having a major and minor area arranged to provide a differential thrust during its respective strokes correlated to the differential resistance developed by the piston rod during its strokes, the said minor area being under constant air pressure and the air motor including air valve means actuated by the air motor piston operable to supply and exhaust the major area in accordance with the piston movements, the minor piston area being correlated to the differential piston rod diameters to produce less resistance to piston rod

movement in the charging stroke than in the discharge stroke causing the air motor piston to complete its charging stroke and actuate the said air valve means to supply air pressure to the major piston area prior to stalling under lubricant back pressure.

11. In a lubricant pump, a cylinder having intake and delivery passageways and piston and valve means for discharging lubricant, an air motor for driving the pump having a motor cylinder, a piston slideable within the cylinder and having a major and minor area at opposite sides thereof, means for maintaining constant air pressure against the minor piston area, piston actuated valve means for admitting air pressure to the major piston area and exhausting the same intermittently in response to piston movements to reciprocate the piston against the constant pressure exerted by the minor area, a pump piston rod connected to the air motor piston, a major delivery pump piston secured upon the said piston rod related to the major area of the motor piston, the piston rod having differential lubricant displacement diameters related to the minor area of the motor piston, the said major area being so proportioned to the minor area to develop a differential thrust sufficient to displace the air maintained against the minor area concurrently with the pressure delivery of the major lubricant charge by the pump piston, the piston rod being reciprocated in one direction by the said minor piston area to deliver a minor lubricant charge by piston rod displacement at a given pressure and being reciprocated in the opposite direction to deliver a major lubricant charge by pump piston displacement at substantially the same pressure by air pressure effective against the major piston area.

12. A lubricant pump suitable to transfer lubricant from a lubricant supply to the intake end of a high pressure grease dispensing pump, said lubricant pump comprising a cylinder adapted to be mounted upon the intake end of the grease dispensing pump in a vertical position submerged in the lubricant supply, a nonsealing piston in the cylinder, a piston rod extended upwardly from the piston, a cylinder head on the lower end of the cylinder, the cylinder having intake ports in its lower side wall extending upwardly above the cylinder head part way to the top of the cylinder, whereby the piston when on the level of the top of the intake ports subdivides the cylinder into an upper and a lower compartment the volumes of which are unequal, the volume of the lower compartment being greater than that of the upper, a check valve in the upper end of the cylinder providing one-way passage of lubricant upwardly from the cylinder into the intake end of the grease dispensing pump during the upward stroke of the piston, means connected to the upper end of said piston rod for reciprocating the piston over substantially the full extent of the cylinder whereby the downward stroke of the piston tends to create a void above the piston and a localized positive lubricant pressure below the piston, and a pervious jacket surrounding the ports in outwardly spaced relation to the piston with its upper and lower ends joined to the cylinder above and below the intake ports, the jacket providing an annular trap about the cylinder which is effective to impede the lateral flow of lubricant produced by the downward stroke of the piston, whereby a localized flow of lubricant passes upwardly about the piston to equalize the lesser pressure above it.

13. A lubricant pump suitable to transfer lubricant from a lubricant supply to the intake end of a high pressure grease dispensing pump, said lubricant pump comprising a cylinder adapted to be mounted upon the intake end of the grease dispensing pump in a vertical position submerged in the lubricant supply, a non-sealing piston in the cylinder, a piston rod extended upwardly from the piston, a cylinder head on the lower end of the cylinder, the cylinder having an intake port in its lower side wall extending upwardly above the cylinder head part way to the top of the cylinder, whereby the piston when on the level of the top of the intake port subdivides the cylinder into an upper and a lower compartment the volumes of which are unequal, the volume of the lower compartment being greater than that of the upper, a check valve in the upper end of the cylinder providing one-way passage of lubricant upwardly from the cylinder into the intake end of the grease dispensing pump during the upward stroke of the piston, means connected to the upper end of said piston rod for reciprocating the piston over substantially the full extent of the cylinder whereby the downward stroke of the piston tends to create a void above the piston and a localized positive lubricant pressure below the piston, and a pervious jacket surrounding the port in outwardly spaced relation to the piston, the pervious jacket providing a trap effective to impede the lateral flow of lubricant produced by the downward stroke of the piston whereby a localized flow of lubricant passes upwardly about the piston to equalize the lesser pressure above it.

14. A lubricant pump suitable to transfer lubricant from a lubricant supply to the intake end of a high pressure grease dispensing pump, said lubricant pump comprising a cylinder adapted to be mounted upon the intake end of the grease dispensing pump in a vertical position submerged in the lubricant supply, a piston in the cylinder, a piston rod extended upwardly from the piston, a cylinder head on the lower end of the cylinder, the cylinder having intake ports in its lower side wall extending upwardly above the cylinder head part way to the top of the cylinder, whereby the piston when on the level of the top of the intake port subdivides the cylinder into an upper and lower compartment, the volumes of which are unequal, the volume of the lower compartment being greater than the volume of the upper, a check valve in the upper end of the cylinder providing one-way passage of lubricant upwardly from the cylinder into the intake end of the grease dispensing pump during the upward stroke of the piston, means connected to the upper end of said piston rod for reciprocating the piston over substantially the full extent of the cylinder whereby the downward stroke of the piston tends to create a void above the piston and a localized positive lubricant pressure below the piston, and a pervious jacket surrounding the ports in outwardly spaced relation to the piston with its upper and lower ends joined to the cylinder above and below the intake ports, the jacket providing an annular trap about the cylinder which is effective to impede the lateral flow of lubricant produced by the downward stroke of the piston whereby a localized flow of lubricant passes upwardly about the piston to equalize the lesser pressure above it, the piston during upward movement being effective to trap lubricant in the portion of the cylinder above the intake ports for transfer upwardly through the check valve to the grease dispensing pump, the piston having clear-

ance with respect to its cylinder to provide restricted downward passage of lubricant in excess of the intake capacity of the grease dispensing pump.

15. A lubricant pump adapted to extend vertically into a lubricant container to dispense lubricant under high pressure from the container, said lubricant pump comprising an elongated delivery cylinder having a lubricant outlet at its upper end, a delivery piston, an upper piston rod connected to the piston and passing slidably in sealed engagement through the upper end of the cylinder, a motor connected to the upper end of the piston rod for reciprocating the piston rod and piston, an intake check valve sleeve providing one-way passage of lubricant upwardly into the lower end of the cylinder during upward movement of the piston, a check valve associated with the piston providing passage of lubricant upwardly through the piston during downward movement thereof, a charging cylinder mounted upon the lower end of the delivery cylinder, a charging piston in the charging cylinder, a second piston rod extending from the delivery piston downwardly to the charging piston adapted to reciprocate the charging piston in unison with the delivery piston, the second piston rod passing in sealed slidable engagement through the intake sleeve valve and having a diameter which is smaller than the upper piston rod, the upper and

lower piston rods by their sealed engagement at the upper and lower ends of the delivery cylinder and their differential diameters being adapted to displace lubricant from the cylinder during the downward stroke, the charging cylinder having elongated intake ports in its lower extent, the charging piston adapted to draw a partial vacuum in the charging cylinder during the initial portion of the downward stroke and to traverse the intake ports during the remainder of the downward stroke, and a pervious jacket surrounding the cylinder at said intake ports, the jacket providing an annular trap about the cylinder effective to impede the flow of lubricant outwardly whereby a flowing stream of lubricant is deflected by the jacket upwardly about the piston to satisfy the partial vacuum above it during said downward piston stroke.
